CAN OPENER

Denis Farandatos, New York, N. Y.

Application March 9, 1953, Serial No. 341,008

4 Claims. (Cl. 30—9)

1

This invention relates to the problem of sanitation in the opening of cans. The problem is very great in restaurants, army camps, hospitals and the like because of the great number of cans opened in such places. The knives of the can openers become dull, and tend to tear off small pieces of metal from the cans, which fall into the food and are consumed. Those pieces of metal may be injurious to the internal organs of those who consume them. Also, can openers are used, without cleaning the knives, to open many cans, frequently of different foods, so that the edges of the cans become contaminated by food of one sort and transfer traces of it to the contents of different cans.

It is an object of this invention to make a self-cleaning can opener that will gather and safely dispose of such particles of metal and which will continuously clean the edges of can opener knives.

The objects of the invention are accomplished, generally speaking, by a can opener having a circular magnetized knife, and a mechanical scraper associated with the cutting edge thereof and with those portions to which the particles of metal are magnetically attracted and attached. The objects are accomplished by an apparatus of which the figures of the drawing show a preferred example.

Fig. 1 is a fragmentary elevational view of a can opener provided with the invention.

Fig. 2 is a section on line 2—2 of Fig. 1.

Fig. 3 is a plan view showing the working parts of the device of Fig. 1.

There is described in U. S. Patent No. 2,462,416 a type of can opener mechanism to which this invention can be readily applied. In the known construction of that opener there is a frame plate 10 which may be mounted on an appropriate support and upon which the working parts are mounted. The working parts include a rotary gear 11 having a flat face 12 against which the edge of the cutting blade 13 bears in cutting position. The gear teeth 14 extend outward from a position behind the knurled edge 15 of the face 12, which serves to rotate a can by bearing against the edge thereof. The blade 13 is also circular and is connected to a gear 16 which can mesh with gear teeth 14. The gears 14—16 are thus capable of being rotated by a crank 17 which turns a spindle upon which the gear 14 is mounted. A plate 18 is pivotally mounted on the plate 10 and the blade 13 and gear 16 are mounted thereon. A lever 19 moves the plate 18 and thus moves the blade 13 and gear 16 into and out of cooperating relation to plate 12 and gear 14 respectively. Thus far, the structure described is old.

According to my invention, the blade 13, which incises the can, is magnetized so that it will pick up all small particles of metal that may be cut or torn from the can and its walls. Associated with that magnetized blade is a scraper 20 having a bifurcated end 21 the furcations of which

2

straddle the knife and bear lightly against its opposite faces 22, 23, from the cutting edge inwardly so far as desired. The scraper 21 is V shaped, forming a trough into which the particles caught by the knife are scraped by the edges of the slot between the furcations as the knife is rotated.

The scraper 20 is pivotally mounted on a bracket 24 by means of a bolt 25 around which a coil spring 26 is mounted, bearing at one end on the bolt head and at the other end on the bracket 24. The bracket and the scraper may be provided with aligning groove and land 27 which hold the scraper lightly against displacement from contact with the cutter 13. The groove will be in one and the land in the other, the land and groove having inclined sides acting as cams to compress spring 26 when the scraper is pivoted away from the knife.

This combination of the magnetized knife and the mechanical scraper is highly useful, as it keeps food and metal particles picked up by the knife from being returned to the can.

The scraper is shown above the horizontal diameter of the knife, because at that location the scraping is done at a more efficient angle than would be the case on the diameter or below it. The angle between scraper and knife is more conducive to ready transfer of particles. The trough-shape of the scraper is efficient for holding scrapings and for conforming the furcations to the faces of the knife.

As many apparently widely different embodiments of the present invention may be made without departing from the spirit and scope thereof, it is to be understood that the invention is not limited to the specific embodiments, except as defined in the appended claims.

What is claimed is:

1. A can opener having a circular, magnetized knife, mechanical scraper means mounted in association with the said magnetized knife, and means to receive the scrapings removed from said knife by said scraper.
2. A can opener as described in claim 1 in which the receiver means is a trough associated with said knife.
3. A can opener having a pair of cooperating elements for cutting a can, one of said elements being a knife and being magnetized, means for moving said knife into and out of cutting position, and mechanical scraper means mounted in association with the edge of said magnetized knife.
4. A can opener having a circular, magnetized blade, a scraper comprising a trough-shaped metal body having a V-shaped slot the edges of which engage the edge of said knife in operative position, and supporting means for said scraper comprising a pivot enabling the scraper to be moved away from the knife.
